ELECTRONIC PULSE GENERATOR FOR HUMAN BODY THERAPY

Logan D. Gilman, St. Paul, Minn., assignor to Theratron Corporation, St. Paul, Minn., a corporation of Minnesota

Filed July 14, 1961, Ser. No. 65,949

Term of patent 14 years

(Cl. D83—1)

FIG. 1 is a view in perspective of an electronic pulse generator for human body therapy, showing my new design;

FIG. 2 is an enlarged view in side elevation, as seen from the side opposite that shown in FIG. 1;

FIG. 3 is an elevation taken from the bottom of FIG. 2; and

FIG. 4 is an end perspective view taken from the right of FIG. 3.

The dominant features of my design reside in the portions shown in full lines.

I claim:

The ornamental design for an electronic pulse generator for human body therapy, as shown and described.
